OIL SHUT-OFF

James E. Hurn, La Porte, Ind., assignor to De
Luxe Products Corporation, a corporation of
Indians

Application November 25, 1936, Serial No. 112,817

7 Claims. (Cl. 210—131)

This invention relates to an oil shut-off, and particularly to such a device in connection with the operation of internal combustion engines.

In the operation of such engines, and particularly the Diesel type of engine, wherein liquid fuel is employed, the fuel oil frequently contains water which adversely affects the activity of the engine and is quite dangerous to the fuel pump. It is, therefore, important to remove the water from the oil, and various means are provided for this purpose. The object of the present device is to automatically stop the flow of oil whenever water is present in the system. The invention is used primarily in combination with a means for removing water from the oil under normal circumstances, and is designed to operate when such device becomes inoperative. However, it is also adapted to be used without other means for the removal of water, particularly in combination with the better grade fuels and under conditions where water is not likely to get into the fuel.

The invention is illustrated in the drawing, in which—

Fig. 1 is a sectional view of a device embodying shut-off means; Fig. 2 is a cross section of said device along the line 2—2; Fig. 3 is a longitudinal section of a modified form of device; Fig. 4 is a cross section of Fig. 3 along the line 4—4; and Fig. 5 is a longitudinal section of a further modification.

As illustrated, the shut-off device comprises a housing 10, preferably cylindrical in form, provided with a cap 11 seated upon a gasket 12 and removably connected to the housing, for example, by threading. A second cap 11a is similarly secured to the other end of the housing. The interior of the housing is loosely filled with a water-expansible material. This material should be one which is not so affected by oil, or at least which is expansible by water, even after being wet with oil. Screens 15 are provided, as indicated in Fig. 1, to hold the material in place, or a single screen may be used, as shown in Fig. 3. The screens in Fig. 1 are held in place by the spring members 16. The device shown in Fig. 1 is greatly preferred, particularly for systems in which large fluid pressures are employed. The oil is admitted to the shut-off device through the line 13, passes through the material 19, through which the oil passes readily, and passes out through the other screen 15 and the opening 14. In Fig. 3, the oil enters through 13a and passes out through 14a. The screen in this instance is a close mesh silken

bag which seats upon a flap in the mouth of said bag, being seated upon shoulder 12 in the housing 10 and there secured by the cap 11. The bag may be completely closed at the top or a screen may be provided across the opening 14a. 5

The structure shown in Fig. 5 comprises a housing 20 into which the oil enters through opening 21 and by which it leaves through opening 22. Within the housing is a piston 23 seated upon the annulus 24. The top of the piston is provided with openings 25 through which oil enters, and the base is covered by a screen and/or a disc 26 provided with openings 27 through which oil leaves. The inside of the piston is filled with a water-expansible material 28. 15

In the operation of the shut-off devices the water-expansible material becomes wet with water and expands, thereby becoming impervious to the passage of oil. Preferably, the material employed is gelatin, with which may be mixed a minor percentage of a hygroscopic agent, such as calcium chloride. Other water-expansible mediums may be employed, however. In the case of gelatin, it is preferred that a substantial depth thereof be used so that when the device closes 20 there will be dry gelatin still present. Normally, a three-inch depth of material for a cylinder one and one-half inches in diameter is sufficient. 25 Granular gelatin is preferably employed.

In the devices shown in Figs. 1 and 3, the gelatin expands and compresses the gelatin to a point where it will not pass oil. In Fig. 5 the expansion of the water-expansible material raises the piston 23 and thereby closes the oil inlet 21. The device shown in Fig. 5 may be balanced by 35 admitting the oil centrally to a divided piston and closing the exits, or by admitting from a pair of entrances and withdrawing from a central exit, thereby providing a balanced valve action. 40

In combination with a filter in an internal combustion system, such as a Diesel engine, the shut-off device has no function except to pass the oil until water begins to pass through the filter, or in the absence of a filter, until wet oil 45 is introduced into the system. The water is then absorbed by the shut-off device until it will pass no more oil, at which time the engine ceases to function. The shut-off device is then removed and replaced, or the material therein may be 50 replenished.

The foregoing detailed description has been given for clearness of understanding only and no unnecessary limitations should be understood therefrom, but the appended claims should be 55

construed as broadly as permissible in view of the prior art.

I claim:

1. A shut-off valve adapted to operate in an oil line comprising a passageway, means for admitting oil to and removing oil from the passageway, and a valve in said passageway including a water-expansible water absorptive medium through which the oil passes and by which the valve is actuated to stop the flow of oil therethrough.
2. In an internal combustion system comprising an internal combustion engine provided with an oil fuel line, a valve in the fuel line including a water-expansible, water-absorptive medium through which the oil fuel passes and by which the valve is actuated to stop the flow of oil therethrough.
3. In an internal combustion system comprising an internal combustion engine provided with an oil fuel line, and having an oil filter in said line adapted to remove water from the oil, a valve in the fuel line including a water-expansible, water-absorptive medium through which

the oil fuel passes and by which the valve is actuated to stop the flow of oil therethrough.

4. A fuel oil shut-off valve comprising a housing, means for admitting oil to and removing oil from the housing, and a body of gelatine within the housing through which the oil passes, the depth of the material being adapted completely to shut off the flow of oil therethrough when moistened.

5. A shut-off as set forth in claim 4, in which a minor proportion of a more hygroscopic agent is included with the gelatine.

6. A valve as set forth in claim 1 in which the valve is shut off solely by the resistance of the moistened water expansive medium.

7. An oil shut-off valve comprising a housing, means for admitting oil to and removing oil from the housing, a water expansive medium in the housing through which the oil passes, and means including a movable member actuated by movement of the expansive medium for controlling the flow of oil therethrough.
